UNITED STATES PATENT OFFICE.

PHILIP A. MYERS, OF ASHLAND, OHIO.

PUMP.

SPECIFICATION forming part of Letters Patent No. 319,924, dated June 9, 1885.

Application filed March 7, 1885. (No model.)

To all whom it may concern:

Be it known that I, PHILIP A. MYERS, of Ashland, in the county of Ashland and State of Ohio, have invented a new and useful Improvement in Pumps; and I do hereby declare that the following is a full, clear, and exact description of the same.

My invention relates to hand-pumps, or pumps adapted to be worked by hand or by ¹⁰ a wind-engine.

In the accompanying drawings, Figure 1 represents a side elevation of the pump. Fig. 2 shows the connection between handle and rod. Fig. 3 is a central vertical section of the ¹⁵ pump. Fig. 4 is a modification of the invention as applied to a force-pump. Fig. 5 are detail views of the guides for the rod.

In the form of pump represented in the drawings a pipe, A, preferably of the ordinary kind of water-pipe, is extended upward through the base-plate a, in which it is held by a set-screw. This pipe terminates a little below the position of the spout, and is screw-threaded for connection with the spout-piece. ²⁰ This spout-piece is cast with the spout, and consists of a short tube, b, on which the spout c is formed. The tube b is threaded internally on its lower end for connection with the upper end of the pipe A. The upper end of the ²⁵ pipe b may be preferably enlarged to form a capacious air-chamber having only an opening (with or without a stuffing-box) for the passage of the pump-rod.

As above described, the spout-piece is ³⁰ screwed to the pump-tube, and the pump-tube is held by means of a set-screw to the base-plate a. From the handle-bracket, hereinafter to be described, a cap projects in the ³⁵ line of the pump-rod, and fits snugly over the end of the spout-piece b, serving not only as a guide for the pump-rod, but as a support and bearing for the upper end of the spout-piece. When it is desired, therefore, to adjust the spout, it is only necessary to loosen ⁴⁰ the set-screw at the lower part, which connects the base-plate and the pump-tube, and the spout with its spout-piece and pump-tube may be adjusted in any direction.

The handle-bracket B is preferably of cast-⁴⁵ iron, and is formed with a tubular part, d,

fitted to slip over and turn upon the pipe A. Above this tubular part, and in line therewith, is a cap, e, formed on the bracket and adapted to fit over the upper end of the spout-piece. It also has a guiding-hole for the passage of the pump-rod. The tubular part d may extend down to and rest upon the base-plate, or a piece of pipe f may be interposed; but the bracket turns freely with the pipe d and cap e on the pipe A and spout-piece. ⁵⁵

The handle E is pivoted on the extension g of the bracket. This extension is turned at right angles over the line of the pump-rod, and serves as an upper guide for said rod, which passes through a hole in said extension. A lower guide is provided within the pipe b. (Shown clearly in detail view, Fig. 5, at e'.) The rod passes between cross-bars, and the water passes up through the water-space upon each side of these bars. The end of the ⁶⁰ handle connected to the rod is forked and straddles the pump-rod. It is connected to said rod by links l l, so that the rod is free to reciprocate in a vertical line, and plays between the forked end of the handle. This ⁶⁵ construction of the end of the handle also provides a guide for the rod at this point. In Fig. 4 I have shown this form of handle and links applied to a force-pump. Suitable guides are secured to the pump-stock, and the links ⁷⁰ are preferably made somewhat longer than those in the lift-pumps, otherwise the construction is the same in both pumps. ⁷⁵

This construction renders the pump particularly applicable to be used in connection ⁸⁰ with a wind-engine.

I claim as my invention—

1. The combination, in a pump, of the pump-tube, a spout and spout-piece secured to the upper end thereof, a base-plate, and ⁹⁰ bracket supporting the handle, the lower end of said bracket surrounding the pump-tube, and a projection, e, upon the upper part, forming a bearing for the spout-piece, all substantially as described. ⁹⁵

2. In a pump, the combination of a pump-tube, spout and spout-piece connected thereto, a handle-bracket having its lower part surrounding the pump-tube and supported from the base-plate, the projection e, resting upon ¹⁰⁰

the upper part of the spout-piece, said projection having a guide-opening for the pump-rod, and a second guide, e' , placed within the spout-piece and movable therein in the adjustment of the bracket and pump-rod, all substantially as described.

In testimony whereof I have signed my name

to this specification in the presence of two subscribing witnesses.

PHILIP A. MYERS.
